DESIGN FOR A GOBLET OR SIMILAR ARTICLE

Loyd C. Kelley, Weston, W. Va.

Application August 26, 1940, Serial No. 94,631

Term of patent 7 years

To all whom it may concern:

Be it known that I, Loyd C. Kelley, a citizen of the United States, residing at Weston, in the county of Lewis and State of West Virginia, have invented a new, original, and ornamental Design for a Goblet or Similar Article, of which the following is a specification, reference being had to the accompanying drawing, forming part thereof, in which:

Fig. 1 is a side elevational view of a goblet or similar article, showing my new design; and

Fig. 2 is a top plan view of the bowl portion.

Fig. 3 is a transverse sectional view of the

bowl portion of the goblet, taken along the line 3—3 of Fig. 1 and in the direction of the arrows.

Fig. 4 is a transverse sectional view of the bowl portion taken along line 4—4 of Fig. 1 and in the direction of the arrows.

Fig. 5 is a perspective view of the goblet, only the upper portion of the stem being shown.

The dominant feature of the design resides in the bowl portion, shown in full lines.

I claim:

The ornamental design for a goblet or similar article, as shown and described.

LOYD C. KELLEY.
